Primary Examiner — Paula Allen Greene*(74) Attorney, Agent, or Firm* — Gokalp Bayramoglu**CLAIM**

The ornamental design for an intelligent earphone, as shown and described.

DESCRIPTION

FIG. 1 is a front view of the intelligent earphone;
 FIG. 2 is a back view of the intelligent earphone;
 FIG. 3 is a left side view of the intelligent earphone;
 FIG. 4 is a right side view of the intelligent earphone;
 FIG. 5 is a top view of the intelligent earphone;
 FIG. 6 is a bottom view of the intelligent earphone;
 FIG. 7 is a perspective view of the intelligent earphone; and,
 FIG. 8 is another perspective view of the intelligent earphone.
